Attorney

UNITED STATES PATENT OFFICE

CARL A. RAINWATER, OF SNOHOMISH, WASHINGTON
IDENTIFICATION NEST FOR HENS AND THEIR EGGS

Application filed March 16, 1927. Serial No. 175,790.

My invention relates to identification nests, designed to permit the hens to have free egress from the nest after having gone into the latter, at the same time providing registration means by which the hen is identified, with respect to a particular egg found in the nest, or by which the fact is indicated that the hen has not laid an egg.

These means consist of a registration device upon which the hen, in leaving the nest, will make a mark by a marker which she carries.

The particular object of my invention is to identify the hen, as a "laying" hen, and by marking the egg laid by her at the time, identify the latter as that of a particular hen. To this end my improved nest comprises an egg-receptacle progressively advanced by devices operated by contact therewith of the hen in leaving the nest; such egg-receptacle being divided by partitions into a series of egg pockets, and the nest in which the hen deposits her egg, being tilted, thus deposits the egg in one of said pockets; this being accomplished by simple devices also operated by contact therewith of the hen in leaving the nest.

I provide further simple means for moving a strip of paper, carried by the registration device, progressively in time with said egg-receptacle. Thus, by dividing said strip of paper into aliquot parts, corresponding with the spacing of the partitions of said egg-receptacle, and providing means for the progressive relative movement of these parts of my nest, a particular hen which has used the nest may be identified in connection with a particular egg found in a pocket of said egg-receptacle, or with an empty pocket thereof, the latter event indicating that the hen is a non-laying hen.

A still further object of my invention is to control the inlet and exit passage-way of my nest by doors, so that entrance to the nest may only be had through its entrance passage-way, and the door guarding the exit being adapted to be swung outward only, as by a hen leaving the nest.

A still further object of my invention is to provide simple means whereby the door guarding the entrance to my nest is locked in

closed position by devices operated by the passage of the hen into my nest.

A still further object of my invention is to provide a simple and reliable marking device adapted to be carried on the back of the hen, without annoyance or irritation to her, which will imprint a legible mark on the said strip of paper as she leaves the nest, and thus identify the hen with the egg she lays, or if she should not have laid an egg to indicate that fact, the marker carried by the hen being positioned on the hen so that no matter if she crouches as she leaves the nest, the marker is bound to register on the said paper.

A still further object of my invention is to provide a nest of the character described which shall be inexpensive to the manufacturer and efficient in its operations.

These features of my invention, the details of construction of my segregating nest, and the operation of its various devices, by themselves and conjointly, are hereinafter fully described with reference to the accompanying drawings:

In said drawings:

Fig. 1 shows a diagrammatic perspective view of my segregating nest, the near side being partially broken away, and the recording mechanism removed, thus illustrating the operative parts of my invention in full and broken lines;

Fig. 2 shows a diagrammatic side elevation of the exit door and the operating means connected thereto;

Fig. 3 shows a diagrammatic side elevation of the entrance doors;

Fig. 4 shows a top plan view of my segregating nest and illustrates the relative arrangement of the passage-ways and the nest and the location of the recording device;

Fig. 5 shows a diagrammatic vertical longitudinal section of my segregating nest, and illustrates the details of construction of the recording mechanism, and the operation thereof;

Fig. 6 shows an enlarged section taken through the entrance door, illustrating part of the operating mechanism of the recording device;

Fig. 7 shows a perspective view of the marking device carried by the hen; and

Fig. 8 shows the marking device in position on the back of the hen, and illustrates, by broken lines, the method of mounting the same.

My segregating nest comprises a roofless box-like housing *a* adapted to be covered in any desirable manner and provided with an inlet passage-way *b*, which leads into a laying or nest chamber *e*. The entrance of the inlet passage is controlled by a door *c*, and in said passage-way is provided a swinging frame or member *d*. An outlet passage-way *f* is provided with an exit door *g*. A partition *h* separates the entrance and exit passage-ways and the said passage-ways are provided with a floor *i*.

The entrance door *c* is hinged to the floor *i* of the passage-way inside the threshold, on a transverse rod *j*, and when opened, normally lies in a horizontal position thereon. As shown in Fig. 2, a rod *k* is hinged to the door *c* as at *l* and the other end of the rod *k* is loosely held in a hole *d'* in the frame *d* by a nut *k'* on the end of the rod *k*.

The frame *d* is of inverted U-shape and is hinged near the top of the passage-way on one side on a pin *m* in the side wall of the housing, and at its other side is mounted on a shaft *n* which extends a short distance into the passage-way *b* and through the partition *h* to the side wall *a'* of the housing *a*, and is provided with a notched portion *o* in which a flat spring *p*, fixed on the frame *d*, normally engages and thus as the frame *d* is opened, the shaft *n* is rotated as hereinafter described.

The floor of the nest chamber *e* is constructed of square mesh netting *s*, and is hinged at its forward corners by means of two upstanding arms *t* and *u*, which are pivoted in the side walls of the housing as at *t'* and *u'*.

An apron 2 of canvas or similar material is fixed underneath the bottom *s* of the nest chamber between the end wall of the housing and the forward part of the nest chamber, which normally supports it and prevents dirt from falling through on the eggs, as herein-after described.

On the forward end of the nest chamber *e* is provided a downwardly extending rectangular member 4, which is adapted to swing in a forward direction but is provided with a stop to prevent it from swinging in a rearward direction.

Adjacent the nest chamber *e* and in the floor of the passage-ways are provided transverse portions 5 and 6 slightly inclined towards a center portion which is entirely cut away and thus the egg is guided as it rolls from the nest to fall into an egg receptacle 7, as herein-after described.

The egg receptacle 7 comprises a number of longitudinally arranged pockets 8 which

are separated by vertical dividers 9 and the said receptacle is arranged centrally and longitudinally of the housing, and is supported thereunder by means of parallel rods 10 and 11 fixed to the bottom of each end of the housing, on which the receptacle rests, but on which it is longitudinally movable.

The upright arm *u* is provided with an extended portion *u2*, to the end of which is pivoted a rod 12, the other end of which is pivoted on the exit door *g* as at *12a*.

The door *g* is also of inverted U-shape and is hinged at its top as at *13* to the partition *h*, and the side wall *a'* of the housing. A bent wire 14 is fixed to the door *g* which extends around the partition *h* and engages the top of the door *c* when it is raised, and thus maintains it in an upraised or closed position, Fig. 3. Within the passage-way *f* is arranged my recording device which is supported at one end from a transverse piece 29, extending across the housing *a*, by a pendent wire 15 which is hooked into a slot 15a, and the carriage is supported at its other end by a flexible connection 16 such as a cord or chain, 90 fastened to the carriage as at 28.

This recording device comprises a carriage 20 in which are arranged an ink pad 18 and a paper roll 17, rotatably mounted on a pin 17a and a bridge section 19, under which the strip of paper 21 is passed, and then upward over a roller 22, which is fixed on the shaft *n*. A friction roller 23 is arranged, bearing on the roller 22, and on the strip of paper 21, thus serving to hold the strip of paper closely around the roller 22. The strip of paper 21 then passes under a guide 24 and is turned back to be conveniently torn off against the edge 24a arranged transversely of the top of the carriage.

A curved guide plate 25 is provided adjacent the ink pad 16 to guide the marker onto the said ink pad.

The marking device I provide, see Figs. 7 and 8, is preferably constructed wholly of wire and adapted to be fastened on the back of the hen. The said marking device is saddle-like in form and comprises curved complementary side members 30 secured together by a transverse arch member 32.

A U-shaped longitudinally arranged, backwardly extending tie member 34 is secured at its ends to the middle of the said transverse member and is bent upwardly so that the middle portion 34a forms a transverse journal pin above the saddle, upon which a roller 33 is journaled. An annular rubber stamp 33a is preferably secured on said roller having a series of numbers assigned to the particular hen on which the marking device is fastened.

The rearward ends 30b of the said side members are curved upwardly and secured to respective sides of the tie member 34, and the opposite or forward ends 30a of the said

side members are curved upwardly and backwardly, as shown in Fig. 7, and are flexible so as to be readily positioned under the wings of the hen, as shown in Fig. 8, by bending the 5 ends 30a downward, as shown in the broken line position of Fig. 7, to rest on the shoulders of the hen's wings.

Further, with my marking device the roller, 33, is so positioned as to be supported on 10 the broad portion of the hen's back, to the rear of the wings, so that when she leaves the nest, she cannot avoid bringing the roller 33 into contact with the ink pad, 18, and the paper strip, 16, because it has been learned 15 from observation that it seems to be the habit of a hen when passing under an obstruction, to push her head and shoulders through, and then draw the rest of her body after her, allowing her tail portion to rub against the 20 obstruction as it may; thus assuring that a number of identification marks will be made by the hen on the paper strip, and assuring legibility of such mark.

Thus it may be clearly seen that the wings 25 of the hen, having been passed through the loops, my marking device will ride securely on the back of the hen, out of the way and of no annoyance to the hen.

The operation of my identification nest is 30 as follows:

A hen upon entering the nest through the inlet passage-way b pushes through the frame d, lifting it somewhat, which raises the entrance door c, by means of the rod k, 35 until the top of the door catches in the curved wire or latch 14 and the door c is thus held closed, and another hen may not enter.

At the same time, the spring p, bearing in 40 the notched portion o of the shaft n, rotates the latter and the roller 22, fixed on said shaft, and thus draws a clean section of the strip of paper 21 under the bridge section 19 of the recording device.

The hen after passing through the frame 45 d, which swings closed behind her enters the nest chamber e and lays her egg. After laying her egg, or if she does not lay, she will pass through the outlet passage-way f and the rotatable marker fixed to her back will 50 first as before mentioned pass under the ink pad 16, become impregnated with ink and then over the strip of paper 21, which is under the bridge section 19, and mark the strip of paper with her number which is provided 55 on the roller.

I have suspended my recording device in 56 such a way as to allow limited vertical movement, which permits the recording device to adjust itself to the height of the hen, but 60 which will not allow the carriage to wobble, which would tend to blur the imprint of the roller on the strip of paper.

The hen after passing under the recording 65 device, pushes through the exit door g which is also U-shaped, lifting it somewhat,

which disengages the latch 14, carried by the said exit door g, from the door c and allows it to fall open. At the same time, the rod 12 which is fixed at its respective ends to the door g and the portion u2 of the nest e, is 70 drawn forward which tilts the nest e, so that the egg 50, which has been laid rolls forward and is guided by the inclined portions 5 and 6 to fall into a pocket 8 of the egg receptacle 7, as best shown in Fig. 2. A buffer 40 is 75 provided on the edge of the floor i adjacent to the nest e so that the egg 50 will not tend to become broken by striking against it.

The rectangular member 4 as the nest is 80 tilted, passes over the dividers 9, but as the nest e returns to its normal position, the said member will push the egg-receptacle 7 forward one pocket.

Thus the hen having passed out of my 85 identification nest has opened the entrance door c for the next hen, and another pocket in the egg receptacle has been moved up to receive the next egg laid.

The next hen in passing through the entrance passage-way will rotate the shaft n 90 and again bring a clean strip of paper under the bridge section 19, on which she will be recorded on passing out.

Of course if a hen does not lay when in the nest, the pocket corresponding to the order 95 of her number on the strip of paper will be moved forward just the same, though empty and it will thus be shown that she did not lay.

In any event, the order of the numbers on 100 the strip of paper will correspond with the order of the pockets in the receptacle. That is, the first number will correspond with the first pocket and so on, and whether the pocket contains an egg or not, will show the record 105 of the hen. Of course, a hen which does not enter the nest at all will be unrecorded and consequently will be classed among the non-layers.

A section 41 of the egg-receptacle is turned 110 outwardly and when the receptacle has been moved to the limit of its forward movement, the section 41 will engage a downwardly extending lever 42, which when the section 41 engages the said lever will rotate a rod 43 115 on which is also provided a lever 44 which as it is moved upward lifts a pin 45, which will block the frame d so that it may not be opened by a hen until the egg receptacle 120 has been emptied and the nest prepared for 125 use again.

I claim:

1. An identification nest comprising a housing provided with an interior nest-chamber and with inlet and outlet passage-ways connecting with the nest chamber, a door controlling the entrance to the inlet passage-way, a member pivoted in said inlet passage-way in front of said nest-chamber, an operative connection between said mem- 130

ber and said door to close the latter, said member arranged to be moved by the hen passing into the nest-chamber, means for securing said door when closed, a swinging frame in the entrance of said nest-chamber and an egg-holding nest carried by such frame, an egg-receptacle into which said nest discharges when said frame is tilted, means operated by contact therewith of the hen leaving the housing, adapted to tilt said swinging frame thereby to empty said nest into said egg-receptacle, a registration device located in said outlet passageway, said device including means for holding, and advancing, a strip of paper in position to receive a mark from a marker carried by a hen passing through said exit passage-way, said strip-holding means operatively connected with the pivoted member in said inlet passage-way, whereby the strip is advanced, and a door controlling the exit of the housing and an operative connection therefrom to said swinging frame.

2. In an identification nest, a housing provided with an interior nest-chamber and with inlet and outlet passage-ways connecting with the nest-chamber, a door controlling the entrance to the inlet passage-way, a member pivoted in said inlet passage-way in front of said nest-chamber, an operative connection between said member and said door to close the latter, said member arranged to be moved by the hen passing into the nest-chamber, a swinging frame in the entrance of said nest-chamber and an egg-holding nest carried by such frame, an elongate longitudinally slidable egg-receptacle, divided into a series of egg-pockets, into which said nest discharges when said frame is tilted, a member carried by said swinging frame adapted in one position of the latter to engage with said egg-receptacle, thereby to advance the latter, a registration device located in said outlet passage-way, said device including means for holding, and advancing, a strip of paper in position to receive a mark from a marker carried by a hen passing through said exit passage-way, and a door controlling the exit of the housing and an operative connection therefrom to said swinging frame.

3. In an identification nest, a housing provided with an interior nest-chamber and with inlet and outlet passage-ways connecting with the nest-chamber, a door controlling the entrance to the inlet passage-way, a member pivoted in said inlet passage-way in front of said nest-chamber, an operative connection between said member and said door to close the latter, said member arranged to be moved by the hen passing into the nest-chamber, means for securing said door when closed, a swinging frame in the entrance of said nest-chamber and an egg-holding nest carried by such frame, an elongate longitudinally

slidable egg-receptacle divided into a series of egg-pockets, into which said nest discharges when said frame is tilted, a member carried by said swinging frame adapted in one position of the latter to engage with said egg-receptacle, thereby to advance the latter, a registration device located in said outlet passage-way, said device including means for holding, and advancing, a strip of paper in position to receive a mark from a marker carried by a hen passing through said exit passage-way, and a door controlling the exit of the housing and an operative connection therefrom to said swinging frame, and another operative connection of said exit door with said entrance-door securing means, whereby to release the latter by the outward swing of said exit-door.

4. In a nest, the combination of a housing, provided with inlet and outlet passage-ways and a nest chamber, an outwardly swinging door hinged at the entrance of said inlet passage-way, an inwardly swinging door-frame, hinged inwardly of said entrance door in said entrance passage-way, a rod connecting said door and said door frame, whereby the entrance door is swung into its closed position by the inward movement of said inward door frame and a swinging exit-door frame in said outlet passage-way, a latch carried by said exit door frame, said latch adapted to be engaged by said entrance door when assuming its closed position, and to be disengaged from the entrance door by the swinging of said exit-door frame.

5. In a nest, the combination of a housing, provided with inlet and outlet passage-ways and a nest chamber, an outwardly swinging door hinged at the entrance of said inlet passage-way on an axis located at the floor thereof, an inwardly swinging door frame, hinged inwardly of said entrance door in said entrance passage-way, a rod connecting said door and said door frame, whereby the entrance door is swung into its closed position by the inward movement of said inward door frame and a swinging exit-door-frame in said outlet passage-way, a latch carried by said exit door frame, said latch adapted to be engaged by said entrance door when assuming its closed position, and to be disengaged from the entrance door by the swinging of said exit-door frame.

6. In a nest, in combination of a housing including a nest chamber and entrance and exit doors therefor, a U-shaped frame pendently hinged at the entrance of the nest-chamber and carrying a rigid horizontally disposed receiving-net, an egg receptacle divided into a series of pockets by transverse partitions into one of which pockets the said net discharges when inclined, a connection between said U-shaped frame and said exit door whereby when the latter is swung outward

said net will be inclined into its discharging position and a recording device comprising means for holding a strip of paper in position to receive a mark from a marker carried by a hen leaving the nest chamber, said means operable to advance said strip by contact of the hen therewith in passing to the nest chamber.

5

titions into one of which pockets the said net discharges when inclined, a connection between said U-shaped frame and said exit door whereby when the latter is swung outward said net will be inclined into its discharging position, a recording device comprising means for holding a strip of paper in position to receive a mark from a marker carried by a hen leaving the nest chamber, said means

70

7. In a nest, in combination of a housing including a nest chamber and entrance and exit doors therefor, a U-shaped frame pend-
ently hinged at the entrance of the nest-cham-
ber and carrying a rigid horizontally dis-
posed receiving-net, an egg receptacle di-
vided into a series of pockets by transverse
partitions into one of which pockets the said
net discharges when inclined, a connection
between said U-shaped frame and said exit
door whereby when the latter is swung out-
ward said net will be inclined into its dis-
charging position, a recording device com-
prising means for holding a strip of paper
in position to receive a mark from a marker
carried by a hen leaving the nest chamber,
said means operable to advance said strip
by contact of the hen therewith in passing to
the nest-chamber and means on said frame
arranged to engage with one partition of said
egg-receptacle and advance the latter to
place another pocket in egg-receiving posi-
tion by the return swing of said frame.

10 by a hen leaving the nest chamber, said means
operable to advance said strip by contact
of the hen therewith in passing to the nest-
chamber, means on said frame arranged to
engage with one partition of said egg-recep-
tacle and advance the latter to place another
pocket in egg-receiving position by the return
swing of said frame, means for locking said
entrance door in closed position, such means
operated by said egg-receptacle when the
same is further moved after its last pocket
has been placed in egg-receiving position and
a buffer located to arrest the egg rolling down
the said net when inclined to discharge into a
pocket of said egg receptacle.

15 10. In a nest, in combination of a housing
including a nest chamber and entrance and exit
doors therefor, a U-shaped frame pend-
ently hinged at the entrance of the nest-cham-
ber and carrying a rigid horizontally dis-
posed receiving-net, an egg receptacle di-
vided into a series of pockets by transverse
partitions into one of which pockets the said
net discharges when inclined, a rod con-

8. In a nest, in combination of a housing including a nest chamber and entrance and exit doors therefor, a U-shaped frame pendently hinged at the entrance of the nest-chamber and carrying a rigid horizontally disposed receiving-net, an egg receptacle divided into a series of pockets by transverse partitions into one of which pockets the said net discharges when inclined, a connection between said U-shaped frame and said exit door whereby when the latter is swung outward said net will be inclined into its discharging position, a recording device comprising means for holding a strip of paper in position to receive a mark from a marker carried by a hen leaving the nest chamber, said means operable to advance said strip by contact of the hen therewith in passing to the nest-chamber and means on said frame arranged to engage with one partition of said egg-receptacle and advance the latter to place another pocket in egg-receiving position by the return swing of said frame and means for locking said entrance door in closed position, such means operated by said egg-receptacle when the same is further moved after its last pocket has been placed in egg-receiving position.

35 9. In a nest, in combination of a housing including a nest chamber and entrance and exit doors therefor, a U-shaped frame pendently hinged at the entrance of the nest-chamber and carrying a rigid horizontally disposed receiving-net, an egg receptacle divided into a series of pockets by transverse partitions into one of which pockets the said net discharges when inclined, a connection between said U-shaped frame and said exit door whereby when the latter is swung outward said net will be inclined into its discharging position, a recording device comprising means for holding a strip of paper in position to receive a mark from a marker carried by a hen leaving the nest chamber, said means operable to advance said strip by contact of the hen therewith in passing to the nest-chamber and means on said frame arranged to engage with one partition of said egg-receptacle and advance the latter to place another pocket in egg-receiving position by the return swing of said frame.

40 10. In a nest, in combination of a housing including a nest chamber and entrance and exit doors therefor, a U-shaped frame pendently hinged at the entrance of the nest-chamber and carrying a rigid horizontally disposed receiving-net, an egg receptacle divided into a series of pockets by transverse partitions into one of which pockets the said net discharges when inclined, a connection between said U-shaped frame and said exit door whereby when the latter is swung outward said net will be inclined into its discharging position, a recording device comprising means for holding a strip of paper in position to receive a mark from a marker carried by a hen leaving the nest chamber, said means operable to advance said strip by contact of the hen therewith in passing to the nest-chamber and means on said frame arranged to engage with one partition of said egg-receptacle and advance the latter to place another pocket in egg-receiving position by the return swing of said frame.

45 11. In a nest, in combination of a housing including a nest chamber and an exit door, a U-shaped frame pendently hinged at the entrance of the nest-chamber and carrying a rigid horizontally disposed receiving-net, an egg receptacle divided into a series of pockets by transverse partitions into one of which pockets the said net discharges when inclined, a connection between said U-shaped frame and said exit door whereby when the latter is swung outward said net will be inclined into its discharging position, means

50 115 120

9. In a nest, in combination of a housing including a nest chamber and entrance and exit doors therefor, a U-shaped frame pendently hinged at the entrance of the nest-chamber and carrying a rigid horizontally disposed receiving-net an egg receptacle divided into a series of pockets by transverse par-

clined into its discharging position, means on said frame arranged to engage with one partition of said egg-receptacle and advance the latter to place another pocket in egg-receiving position by the return swing of said frame, means for locking said entrance door in closed position, such means operated by

said egg-receptacle when the same is further moved after its last pocket has been placed in egg-receiving position and a buffer located to arrest the egg rolling down the said net 5 when inclined to discharge into a pocket of said egg receptacle.

12. A marking device adapted to be secured on a hen to cooperate with recording means provided on an identifying nest, said marking device comprising a frame constituting a saddle adapted to be placed on the hen's back, said frame made wholly of wire and comprising side members, an arch transverse member connecting the side members intermediate their ends; said side members at one end of the saddle being arranged to conform with the arch of said transverse member spaced from the latter, the opposite ends of the side members constituting flexible extensions 10 adapted to be fastened on the shoulders of the hen's wings, a tie element connecting said transverse member with said curved ends of the side members, said tie element carrying a journal pin above the saddle, 15 a marking roller journaled on the journal pin, 20 a marking roller journaled on the journal pin.

13. A marking device adapted to be secured on a hen to cooperate with recording means provided on an identifying nest, said marking device comprising a frame constituting a saddle adapted to be placed on the hen's back, said frame made wholly of wire and comprising side members, an arch transverse member connecting the side members intermediate their ends; said side members at one end of the saddle being arranged to conform with the arch of said transverse member spaced from the latter, the opposite ends of the side members constituting flexible extensions 30 adapted to be fastened on the shoulders of the hen's wings, a tie element connecting said transverse member with said curved ends of the side members, 35 a marking roller journaled on the journal pin, 40 a marking roller journaled on the journal pin.

14. A marking device adapted to be secured on a hen to cooperate with recording means provided on an identifying nest, said marking device comprising a frame constituting a saddle adapted to be placed on the hen's back, said frame made wholly of wire and comprising side members, an arch transverse member connecting the side members intermediate their ends; an extension of said side members at one end of the saddle, the opposite ends of the side members constituting flexible extensions 50 adapted to be fastened on the shoulders of the hen's wings, a tie element connecting said extension of the side members with said transverse member, said tie element carrying a journal pin above the saddle, a marking roller journaled on the journal pin, 55 a marking roller journaled on the journal pin.

CARL A. RAINWATER.
